(57) **CLAIM**

The ornamental design for a self-attaching electronic label holder, as shown and described.

DESCRIPTION

FIG. 1 is a front perspective view of a self-attaching electronic label holder in an environment of use;

FIG. 2 is a back perspective view of a self-attaching electronic label holder in an environment of use;

FIG. 3 is a perspective view taken from the front, top, left side of the self-attaching electronic label holder showing our new design, an attaching portion being shown in an open position;

FIG. 4 is a perspective view taken from the back, bottom, right side thereof;

FIG. 5 is a front elevational view thereof;

FIG. 6 is a back elevational view thereof;

FIG. 7 is a side elevation view from the right-hand side thereof;

FIG. 8 is a side elevation view from the left-hand side thereof;

FIG. 9 is a top plan view thereof;

FIG. 10 is a bottom plan view thereof;

FIG. 11 is a perspective view from the top, front, right side of a self-attaching electronic label holder showing the attaching portion in a closed position; and,

FIG. 12 is a side elevation view from the right-hand side thereof.

The broken lines in FIGS. 1 and 2 illustrate the environment, including an electronic price label module and a wire fixture, in which the self-attaching electronic label holder may be used and form no part of the claimed design.
